(57) **CLAIM**

The ornamental design for a function key and key matrix area for a handset, as shown and described.

DESCRIPTION

FIG. 1 is a front view of a function key and key matrix area for a handset showing my new design; and,

FIG. 2 is a perspective view thereof.

The broken line showing of the remainder of the handset is for illustrative purposes only and forms no part of the claimed design.

1 Claim, 1 Drawing Sheet

FIG. 1

FIG. 2
